UNITED STATES PATENT OFFICE.

GEORGE SALAMAN, OF LONDON, ENGLAND.

DEVICE FOR USE IN SAVING LIFE AT SEA.

1,322,828.

Specification of Letters Patent. Patented Nov. 25, 1919.

Application filed February 10, 1919. Serial No. 276,048.

To all whom it may concern:

Be it known that I, GEORGE SALAMAN, a subject of the King of Great Britain, late of No. 4 Circus street, Marylebone Road, 5 London, England, now residing at No. 1^a Victoria avenue, Bishoptsgate, in the city and county of London, England, have invented certain new and useful Improvements in or Relating to Devices for Use in 10 Saving Life at Sea, of which the following is a specification.

The present invention relates to devices for use in saving life at sea and its main object is to provide means for preserving the 15 kit or clothing of or for the persons using the devices so that after rescue the persons saved have at hand proper clothing for wear and at the same time to provide means for the said purpose which shall be more reliable and economical than those heretofore known. The said invention is therefore mainly and particularly applicable for use by members of His Majesty's forces on the sea.

According to the said invention there is provided a bag, container or inclosure the body of which is of flexible waterproof material and may be charged with kit or clothing with or without food, furnished with 20 provisions by means of which it may be opened and closed for placing the kit or clothing within it and removing the same. There may also be provided means for applying the device in proper position to the 25 body of the user. The said inclosure when so filled and closed in a watertight manner is buoyant and therefore constitutes a life buoy, and acts similarly to an ordinary life buoy, while at the same time the kit or clothing of the person using the device is 30 preserved for use after rescue. The said invention also consists in constructing an inclosure as hereinbefore described in a tubular form with means for connecting the ends 35 together so that after the clothing has been placed within it, and the ends so secured, it is in suitable form for encircling the body. The said invention further consists in certain other features hereinafter described 40 and claimed.

In order that the said invention may be clearly understood and readily used in prac-

tice, it is hereinafter described with reference to the accompanying drawings, which illustrate a convenient embodiment of the 55 said invention.

Figure 1 of the said drawings is a view of the device when ready for use showing that side which is uppermost when on the 60 body.

Fig. 2 is a view of the device when on the body looking toward the front.

Fig. 3 is a view of the device when on the body looking at one side thereof.

Fig. 4 is a fragmentary sectional view of 65 the part of the device where the ends of the inclosure are detachably secured together and showing them so secured.

Fig. 5 is a view looking from above, of one of the fastening devices, by use of which 70 the ends of the inclosure are detachably secured together.

Figs. 1, 2 and 3 are somewhat diagrammatic and Figs. 4 and 5 are drawn to a larger scale than Figs. 1, 2 and 3. 75

In the following description the parts of the said drawings are referred to by the letters and numerals marked thereon, the same letters and numerals indicating the same parts in all the said figures. 80

a is the inclosure which is of tubular form constituting a receptacle of sufficient size to contain the kit or clothing of the person for which the device is designed and when so filled and its ends connected together of 85 sufficient size to encircle the body just below the arms, preferably with a free space between the inner part of the device and the body. The inclosure is made of waterproof, or waterproofed, fabric and preferably of 90 two layers of fine canvas secured together face to face by a solution of india-rubber between them. In some cases where it is desirable that the outer layer of canvas shall be rendered non-absorbent, its outer 95 face may be rendered waterproof by application thereto of a suitable waterproofing material. The two ends of the tubular inclosure *a* are provided respectively with metal collars *a'* and *a²* in order that the 100 said ends may be detachably secured together in a convenient manner. These collars *a'* and *a²* are of suitable metal such as brass, and are provided with devices by

which they may be readily secured together face to face, or released one from the other. The said fastening devices consist of studs b , b on the collar a' and toggle levers and links b' , b^2 mounted on the other collar a^2 . There are preferably three of the said fastening devices arranged equidistantly around the collars and their construction is best illustrated in Figs. 4 and 5. The toggle levers b' are pivoted to the collar a^2 and are provided with suitably formed extensions by which they may be manipulated. To the toggle levers, links b^2 are pivoted, which links are provided at their outer ends with openings by which the said ends may be passed over the studs b , which studs are recessed on their far side. When the toggle levers b' are turned up as indicated in broken lines in Fig. 4, the ends of the links b^2 may be readily passed over the studs b and when the said toggle levers are turned down, the links b^2 are drawn to bear tightly against the recessed parts of the studs b thus drawing the two collars together. The end of the tubular inclosure a to which the collar a^2 is secured is permanently sealed by a metal diaphragm a^3 secured within the collar a^2 . The other end of the tubular inclosure a is that through which it is filled with the kit or clothing and is provided with a flexible tubular appendage a^4 of waterproof material the mouth of which may be closed by a rubber ring a^5 passed over the free end of the said appendage. In order that the mouth of the said appendage may be tightly closed in practically a water-tight manner, the india-rubber ring a^5 may conveniently be doubled over the mouth of the said appendage as shown in Fig. 4, and in order that the said ring may not be misplaced when not in use it may be conveniently connected by a tape to the inner end part of the said appendage a^4 . As the appendage a^4 is of waterproof material and may be readily closed in practically a water-tight manner, it is not essential that the junction between the collars a' , and a^2 should be absolutely water-tight, although it is preferable that it should be, in order to avoid decreasing the buoyancy of the device by entry of water through the said junction. A resilient packing ring c is therefore preferably provided as shown in Fig. 4 in an annular recess in the collar a' against which ring an annular projection or rib on the collar a^2 bears with some pressure when the toggle lever fastening devices are in operation. The flexible fabric of which the body of the tubular inclosure a is constituted is connected to the collars a' and a^2 by providing the said collars with annular extensions somewhat thinner than the parts of the collars abutting against each other, and thin metal rings d , d . The respective ends of the flexible body of the inclosure a

are placed within the extensions of the collars a' , a^2 and the rings d , d are then placed within the ends of the flexible material and caused to grip the said material between the faces of the said extensions and the rings d , d by annularly corrugating them and pressing the rings d , d from within by means of rollers as is well known for such purposes. In the case of the collar a' the appendage a^4 is secured in place by its inner end being turned around and disposed against the inner side of the end of flexible material of which the body of the inclosure a is made before insertion of the ring d so that when the ring and extension are forced together and corrugated, both the end part of the said flexible material and the inner end part of the appendage a^4 are gripped together in practically a water-tight manner between the said extension and ring. When the device is in use it is convenient that the ends of the inclosure a secured together by the rings a' , a^2 and the fastening devices carried by them, should be between the arm of the user of the device and the front part of his body, as indicated in Fig. 1. The device is applied to or supported on the person by means of the flexible part e having an opening e' which may be passed over the head so that the portions on each side of the said opening rest upon the shoulders. This part e may be conveniently made of strong textile material such as canvas preferably rendered waterproof in order to avoid absorption of water by it, and it is conveniently secured to the tubular inclosure a by a portion of the part e being turned and secured around the said inclosure at the part which in use will be at the back of the user. At the front, the said part e is provided with a number, say three, of spring snap hooks f , f which may be engaged with metal loops on a part g secured around that part of the tubular inclosure a which will be at the front of the person when in use. By means of the said spring snap hooks therefore the tubular inclosure a when its ends are connected together, may be very readily disposed in proper position on the body, although the said hooks are not essential, and the front portion of the part e may be permanently secured to that portion of the tubular inclosure a which will be at the front when in use, as the inner diameter of the said tubular inclosure a when its ends are connected together is usually such that it may be passed over the shoulders and arms and the arms withdrawn therefrom and disposed on the outer side thereof, so that the device shall be around the body just beneath the arms, which is the preferable position, as indicated in Fig. 2. The device is provided with a strap h of some little length with a spring snap hook h' at its free end, by which the user of the device may secure himself to

another person in the water, or to any body or article in the water to which the user of the device may desire to connect himself. In order to facilitate the use in this manner 5 of the said strap h and hook h' another strap i is provided with a ring i' at its free end. The said straps h and i are secured to the rear of the part e and are used in conjunction by bringing the strap i around the 10 body to the front and then threading the strap h through the said ring i' and pulling it taut as indicated in Fig. 2, whereby the device is firmly anchored on the body, so that any pull on the free part of the strap h will 15 not displace it. Two persons connected together by the hooks and straps h , h' may support a third almost helpless person on the said straps. When the device is not in use, the collars a' , a^2 are disconnected and the 20 tubular container a may be straightened out whereby the device may be stowed with the said container in a collapsed condition and folded up. When it is expected that the device may have to be used, the tubular 25 container a is filled through the appendage a^4 the mouth of which is opened for the purpose, with the kit or clothing or food that the proposed user thinks it desirable to preserve, it being understood that it is preferable 30 that so much kit or clothing with or without food be inserted in the tubular inclosure a as will fill it from end to end. The mouth of the appendage a^4 is then closed and the collars a' and a^2 brought together 35 and the fastening devices carried by them manipulated so as to hold the said collars securely together. The part e is then passed over the head and the device disposed around the body just below the arms 40 and the hooks f , f engaged with the part g so as to support the device in position.

The sealed end of the tubular inclosure a may conveniently be utilized to form a reservoir for drinking water for use by the person using the device, as illustrated in the drawings. This reservoir is formed by securing a diaphragm j at the inner end of the ring d within the collar a^2 and providing an outlet between the diaphragms a^3 , j , at the 45 lower part of the said collar a' . The said outlet is provided with a cock k and a rubber tube h' with mouthpiece. At the upper part of the collar a^2 a small cock l is provided for inlet of air when water is being 50 withdrawn from the reservoir and a filling nozzle provided with a screw closing cap m is also provided at the upper part of the 55 said collar a^2 .

What I claim and desire to secure by 60 Letters Patent of the United States:—

1. A device for use in saving life at sea consisting essentially of a tubular bag or container the body of which is of flexible waterproof material and may be charged

with kit or clothing with or without food, 65 furnished with provisions by means of which it may be opened and closed for placing the kit or clothing within it and removing the same and such that when so charged it may be placed around the body of the 70 user.

2. A device for use in saving life at sea consisting essentially of a tubular bag or container the body of which is of flexible waterproof material and may be charged 75 with kit or clothing with or without food, furnished with provisions by means of which it may be opened and closed for placing the kit or clothing within it and removing the same and having means for securing 80 its two ends together to form an encircling element to surround the body of the user.

3. A device for use in saving life at sea consisting essentially of an inclosure the 85 body of which is of flexible waterproof material and may be charged with kit or clothing with or without food, furnished with provisions by means of which it may be opened and closed for placing the kit or 90 clothing within it and removing the same and with provisions for applying the device in proper position to the body of the user, and with a strap or the like with a hook or the like at its free end by which the user of 95 the device may be secured to another person.

4. A device for use in saving life at sea consisting essentially of a tubular bag or container the body of which is of flexible waterproof material and may be charged 100 with kit or clothing with or without food, furnished with provisions by means of which it may be opened and closed for placing the kit or clothing within it and removing the same and such that when so charged 105 it may be placed around the body of the user, and provided with a strap or the like with a hook or the like at its free end by which the user of the device may be secured to another person. 110

5. A device for use in saving life at sea consisting essentially of a tubular bag or container the body of which is of flexible waterproof material and may be charged with kit or clothing with or without food, 115 furnished with provisions by means of which it may be opened and closed for placing the kit or clothing within it and removing the same and having means for securing its two ends together to form an encircling 120 element to surround the body of the user one end of the said container being sealed and formed into a drinking water reservoir.

6. A device for use in saving life at sea consisting essentially of a tubular bag or 125 container the body of which is of flexible waterproof material and may be charged with kit or clothing with or without food,

furnished with provisions by means of which it may be opened and closed for placing the kit or clothing within it and removing the same and having means for securing its two ends together to form an encircling element to surround the body of the user and an attachment for passing over the head

of the user and resting on the shoulders to support the said bag or container the said attachment having means for detachably connecting it at the front of the user to the portion of the bag or container at that part.

GEORGE SALAMAN.
